APPARATUS FOR BURNISHING SHOULDERS
OF COLLAPSIBLE TUBES

Archibald W. Paull, Sr., Alonzo L. Edwards, and
Walter T. Davis, Wheeling, W. Va., assignors to
Wheeling Stamping Company, Wheeling,
W. Va., a corporation of West Virginia

Application January 16, 1941, Serial No. 374,640

11 Claims. (Cl. 51—108)

This invention pertains to the manufacture of collapsible tubes and more particularly to the burnishing of shoulders of conventional collapsible metal tubes and is for an improvement in an apparatus for so burnishing the tubes.

The invention is particularly applicable to collapsible tubes formed of aluminum, and will be described particularly in connection with the manufacture of aluminum tubes, although it is applicable to tubes formed of other material.

Collapsible tubes for the dispensing of dentifrices, cosmetics, and toilet accessories are most commonly formed of tin. The conventional tube has a threaded neck with a removable cap, an inclined annular shoulder, and a cylindrical body. The cylindrical body of the tube is usually decorated with a decoration such as a printed label, this decoration completely covering the body of the tube. The shoulder alone is usually the only metal surface which is exposed to view. In an extruded tin tube this surface usually has a naturally high polish and luster which adds to the attractiveness of the container. Instead of being made of tin, tubes are frequently formed of aluminum. When aluminum is extruded it becomes quite hard and in order to soften the tube to give it the desired pliability it is necessary to anneal the tube. After annealing the shoulders as well as the body of the tubes are dull and lusterless. The dull surface on the body of the tube is not objectionable because the tube is subsequently decorated, but the dull surface on the shoulder of the tube is quite objectionable from the standpoint of appearance as the finished container is not as attractive as the more expensive tin tube. For these reasons we find it particularly desirable to burnish the shoulders of aluminum tubes in order to give them a high polish and luster and thereby improve their appearance. Likewise the invention is applicable to any other metal tube where it is desirable to improve the luster and polish the shoulder of the tube.

In the manufacture of tubes made from tin, the usual procedure is to extrude the tube after which it is subjected to a number of finishing operations wherein the tube is cut to length, the neck end of the tube is trimmed and threaded, and the cap is applied. In the prior patent of Walter T. Davis, No. 1,678,463, there is disclosed one form of machine for simultaneously operating on a number of tubes to successively perform these operations, including the automatic capping of the tubes. In the manufacture of aluminum tubes, the threads must be chased on the neck before the tube is annealed and softened as the

threads cannot be so satisfactorily cut in the soft aluminum.

According to the present preferred embodiment of the invention, a machine of the general type disclosed in the said Davis Patent No. 1,678,463 having a turret with a number of spindles thereon is employed. The intermittent rotation of the turret carries a spindle successively through a number of stations. According to the present invention, the shoulder of the tube is ordinarily burnished at the one station before the cap is applied to the threaded neck of the tube. It is of course desirable to burnish the neck of the tube before the cap is applied because the cap, being of substantial thickness, would prevent the shoulder of the tube from being burnished across its full width. On the other hand, since the neck of the tube has been previously trimmed and threaded it is very important that no dirt or lint from the buffing wheel enter the open neck of the tube. Our invention provides means for closing the neck end of the tube against any possible entry of foreign particles during this burnishing or buffing operation.

Our invention may be readily understood by reference to the accompanying drawings in which—

Figure 1 is a side elevation of a machine constructed in accordance with our invention and to effect the method which is hereinafter more fully described;

Figure 2 is a view which is partly in end elevation of the machine shown in Figure 1 and partly a transverse section;

Figure 3 is a horizontal section on a somewhat larger scale in substantially the plane of line III—III of Figure 2; and

Figure 4 is a fragmentary detail view showing the means for closing the neck end of the tube.

Referring to the drawings, 2 designates the bed and supporting frame of a machine of the general character shown in the said Davis Patent No. 1,678,463. Supported on the bed of the machine are uprights 3 having bearings 4 thereon supporting a main shaft 5. At one end of the shaft 5 is a disk or turret 6 having a number of independently rotatable mandrels 7 thereon arranged at regularly spaced intervals around the turret near its periphery, the mandrels extending in the direction of the axis of the shaft 5, but of course being eccentrically positioned with respect to the axis of the shaft 5. Each mandrel is provided at the rear surface of the plate or turret 6 with a friction pulley 8. A belt 9 directly engages all but one of these pulleys at the same time. This

belt 9 passes around a driving pulley 10 on a shaft 11 positioned to one side of the shaft 5. The arrangement is such that when the pulley 10 is driven the mandrels at all of the stations except one are directly driven and rotated by the belt 9. At one station, designated 12, the belt passes between the guide pulleys 13 and 13a and the guide pulley 13 engages the pulley 8 of the mandrel at this particular station so that the mandrel at this station may be rotated in a direction opposite to the rotation of the mandrels at all of the other stations.

Mounted on the frame of the machine parallel with the shaft 5 is a power shaft 14 having a drive means such as a pulley 15 at one end thereof. This shaft is geared through gears 16 to operate a second shaft 17 which is parallel with the shaft 14. The shaft 17 is provided with a cam 18 that operates a lever 19 having a pawl mechanism 20 at its upper end for engaging a ratchet wheel 21 on the shaft 5 for intermittently rotating the shaft 5 through a predetermined arc. Where the turret is provided with six spindles or mandrels the ratchet has six teeth. The shaft 17 also carries a second cam 22 which operates a vertically movable rod 23 for actuating a detent 24 and engages a notched wheel 25 on the shaft 5 and which serves to hold the shaft 5 against free rotation so that the spindles or mandrels will be accurately positioned or indexed at their respective stations.

The shaft 17 has a pulley 26 thereon that drives a belt 27 which, in turn, drives a pulley 28 for rotating a cap feed hopper 29. Caps from the hopper 29 are fed down the chute 30 into the automatic capping mechanism 31. This mechanism is substantially the same as that shown in the prior Davis patent referred to and need not be here described in detail. As shown in the said prior patent, the capping mechanism is automatically operated upon the actuation of the machine so that each time that a mandrel is moved to the station opposite the capping mechanism a chuck is thrust forwardly to hold a cap against the end of the tube which is on the rotating mandrel and thus automatically apply the cap to the end of the tube.

Mounted on the top of the frame 2 of the machine is a channel shaped plate or holder 32 in which the base 33 of a motor 34 is slidably received. The plate 32 is set at an angle to the longitudinal axis of the mandrel 7 so that the shaft 35 of the motor is parallel with the sloped shoulder of the tube, as clearly shown in Figure 3. Motor shaft 35 is provided with a buffering wheel 36, the periphery of which is adapted to engage the shoulder of a tube carried on the mandrel 7 when a mandrel 7 is positioned at the buffering station. An adjusting screw 37 enables the motor 34 to be adjusted so that the buffering wheel will properly engage the shoulder of the tube. This adjustment keeps the angular relation between the wheel and mandrel constant and accommodates for wear of the buffering wheel or for a chance of mandrels for different sizes of tubes. The motor 34 is continuously driven so that as each mandrel is successively brought to the buffering station the buffering wheel 36 will engage the shoulder of the tube on the mandrel. At the same time the mandrel itself will be rotated so that the entire annular shoulder of the tube will be buffed or burnished to impart bright luster thereto.

The buffering wheel 36 is of a width such that it will simultaneously buff the full width of the

shoulder of the tube from the base of the threaded neck to the extreme periphery of the shoulder. This is clearly shown in Figure 3. In order to close the end of the tube while it is being buffed and thus prevent any foreign particles from entering the neck of the tube, means is provided for closing the tube during the buffering operation. This means comprises a fiber disk 38 shown in detail in Figure 4 carried on a small metal plate 39. The disk 38 is of a diameter substantially equal to the diameter of the end of the tube. The metal plate 39 is carried on a pin 40 which is slidably and rotatably passed through one end of a lever 41. A compression spring 50 serves to yieldably urge the fiber disk against the end of the tube which it engages. The lever 41 has the shape best shown in Figure 2, the pin 40 being carried on an upright portion 41a of this lever. A pin 42 passes through the lower part of this arm 41a of the lever for pivotally supporting the lever on a bracket 43 carried by the main bed or frame of the machine. Below the pin 42 the lever has a laterally extending portion 41b from the end of which is a depending vertical portion 41c. The lever 41c is provided with a cam engaging roller 44 which engages a cam 45 on the shaft 17. The cam 45, being on the same shaft as the cam 18 which rotates the shaft 5, and the rod 23 which operates the indexing mechanism 24, causes the lever 41 to be rocked in a predetermined relation to the movement of the turret. The arrangement is such that each time a mandrel is brought into position at the buffering station the upper end of the lever 41 is rocked to the right as viewed in Figure 1, causing the fiber pad 38 to be yieldably pressed against the end of the collapsible tube carried on the mandrel. The yielding pressure of the pad against the tube effectively closes the neck of the tube. Since the pin 40 is rotatable in the upper portion 41a of the lever 41, the pad can revolve with the tube during the buffering operation. The timing of the cam 45 is such that just as the mandrel moves away from the buffering station, the upper end of the lever 41 moves toward the left as viewed in Figure 1, withdrawing the pad 38 from engagement with the tube.

The capping station, including the cap-applying chuck 31, is at a station succeeding the buffering station. In the particular machine illustrated, the cap-applying station is located two stations after the buffering station. Referring to Figure 2, if the turret rotates in the direction of the arrow, the capping mechanism is preferably positioned at the station immediately above the reversely rotating spindle at the station marked 12. This is clearly shown in Figure 1 but for the purpose of clearly illustrating the buffering unit the capping mechanism has been omitted from Figure 2.

In operating upon aluminum tubes the aluminum tubes, after being extruded, are threaded, and then annealed. After they are annealed they are applied to the mandrels of the turret 6 preferably by automatic means as illustrated in the said patent to Walter T. Davis, No. 1,678,463. They are applied to the mandrels in the turret at a station preceding the buffering station, preferably being applied at a position two stations in advance of the buffering operation and immediately succeeding the station 12 where the mandrel is rotated in a reverse direction. If the tube has not previously been cut to length it may be cut to length at the succeeding station. It is

then burnished with the neck of the tube closed during the burnishing operation. It is then carried around to the capping station. It is finally removed at the station where the mandrel is designated 12 and where it is reversely rotated, the reversing rotation aiding in the removal of the tube. The rotation of the turret or carrier moves the mandrel element relatively to the burnishing element, thus carrying the mandrels into and out of operative relation with the burnishing element. This is desirable to facilitate the application and removal of tubes from the mandrel.

By the use of the method and machine as herein disclosed and described, the shoulders of the tubes are automatically burnished on the machine which is used for applying caps to the tubes and without requiring any added labor. By reason of the fact that the tubes are burnished before the caps are applied, the shoulders can be polished across their full width. At the same time, by temporarily closing the ends of the tubes, foreign particles cannot get into the ends of the tubes during this burnishing and polishing operation.

While we have illustrated and described one particular embodiment of our invention, it will be understood that the machine may be otherwise constructed, and that various modifications and changes may be made therein. It will also be understood that the invention is not limited to the burnishing or polishing of the shoulders of aluminum tubes, but that the invention is applicable to the processing of any tubes where such additional polishing operation is desired.

We claim:

1. Apparatus for burnishing the shoulders of collapsible tubes wherein the tube has a neck portion, a shoulder portion and a body portion comprising a rotatable mandrel and a cooperating rotatable buffing wheel positioned to engage the full width of the shoulder of a tube when the tube is positioned on said mandrel.

2. Apparatus for burnishing the shoulders of collapsible tubes wherein the tube has a neck portion, a shoulder portion and a body portion comprising a rotatable mandrel and a cooperating rotatable buffing wheel positioned to engage the full width of the shoulder of a tube when the tube is positioned on said mandrel, and means on the apparatus for closing the neck end of the tube while the tube is being engaged by the buffing wheel.

3. Apparatus for burnishing the shoulders of collapsible tubes wherein the tubes have a neck portion, a shoulder portion and a body portion comprising a mandrel element adapted to support a tube to be finished, a burnishing element for engaging the shoulder of a tube positioned on the mandrel, and means for moving one of said elements into and out of operative relation with the other whereby the tubes may be applied to and removed from the mandrel while the two elements are out of operative relation.

4. Apparatus for burnishing the shoulders of collapsible tubes wherein the tubes have a neck portion, a shoulder portion and a body portion comprising a mandrel element adapted to support a tube to be finished, a burnishing element for engaging the shoulder of a tube positioned on the mandrel, means for moving one of said elements into and out of operative relation with the other whereby the tubes may be applied to and removed from the mandrel while the two elements are out of operative relation, and means

for closing the neck end of the tube during the time that the burnishing element is in operative relation with respect to the mandrel.

5. Apparatus for burnishing the shoulders of collapsible tubes wherein the tubes have a neck portion, a shoulder portion and a body portion comprising a mandrel element adapted to support a tube to be finished, a burnishing element for engaging the shoulder of a tube positioned on the mandrel, means for moving one of said elements into and out of operative relation with the other whereby the tubes may be applied to and removed from the mandrel while the two elements are out of operative relation, and means for rotating the mandrel to turn the tube therein while the tube is engaged by the burnishing element.

6. Apparatus for burnishing the shoulders of collapsible tubes wherein the tubes have a neck portion, a shoulder portion and a body portion comprising a turret having a plurality of rotatable mandrels projecting axially therefrom, means for intermittently rotating the turret to progressively present the mandrels to a number of stations, and a burnishing wheel at one station having its periphery positioned to engage and polish the periphery of a tube on the mandrel which is presented to such station.

7. Apparatus for burnishing the shoulders of collapsible tubes wherein the tubes have a neck portion, a shoulder portion and a body portion comprising a turret having a plurality of rotatable mandrels projecting axially therefrom, means for intermittently rotating the turret to progressively present the mandrels to a number of stations, a burnishing wheel at one station having its periphery positioned to engage and polish the periphery of a tube on the mandrel which is presented to such station, and means at said station for temporarily closing the neck of a tube on the mandrel at said station while the shoulder of the tube is being burnished.

8. Apparatus for burnishing the shoulders of collapsible tubes wherein the tubes have a neck portion, a shoulder portion and a body portion comprising a movable supporting element having a plurality of parallel individually rotatable mandrels thereon, means for intermittently presenting the mandrels to a burnishing station, a burnishing element at said station arranged to engage the shoulders of the tubes on the mandrels, and means for rotating the mandrels while they are at said station.

9. Apparatus for burnishing the shoulders of collapsible tubes wherein the tubes have a neck portion, a shoulder portion and a body portion comprising a movable supporting element having a plurality of parallel individually rotatable mandrels thereon, means for intermittently presenting the mandrels to a burnishing station, a burnishing element at said station arranged to engage the shoulders of the tubes on the mandrels, means for rotating the mandrels while they are at said station, and means at said burnishing station for closing the necks of the tubes on the mandrels as the mandrels are brought into position for the burnishing of the tubes thereon.

10. Apparatus for burnishing the shoulders of collapsible tubes wherein the tubes have a neck portion, a conical shoulder portion and a body portion comprising a support having a plurality of individually rotatable mandrels thereon at regularly positioned intervals, means for intermittently moving the support to progressively ad-

vance the mandrels from one station to another, a rotatable shaft having a burnishing wheel thereon at one of said stations, the axis of the shaft being at an angle to the axis of the mandrel at said station whereby the periphery of the burnishing wheel makes full line contact with the conical shoulder of the tube on the mandrel, and means for rotating the mandrel which is engaged by said burnishing wheel.

11. Apparatus for burnishing the shoulders of collapsible tubes wherein the tubes have a neck portion, a conical shoulder portion and a body portion comprising a support having a plurality of individually rotatable mandrels thereon at regularly positioned intervals, means for intermittently moving the support to progressively ad-

vance the mandrels from one station to another, a rotatable shaft having a burnishing wheel thereon at one of said stations, the axis of the shaft being at an angle to the axis of the mandrel at said station whereby the periphery of the burnishing wheel makes full line contact with the conical shoulder of the tube on the mandrel, means for rotating the mandrel which is engaged by said burnishing wheel, and means for adjusting the burnishing wheel with relation to the mandrel while maintaining the same angular relation between the burnishing wheel and the mandrel.
